OPEN ENDED CONTAINER

Frank D. Jonas, East Williston, N. Y., assignor to Oxford Filing Supply Co., Brooklyn, N. Y., a partnership composed of Richard A. Jonas, Richard A. Jonas, Jr., Robert P. Jonas, Frank D. Jonas, and Edward F. Jonas

Application February 23, 1932. Serial No. 594,541

4 Claims. (Cl. 229—16)

One of the objects of this invention is to provide a strong, rigid, durable, outer container or casing within which a sliding drawer may be employed to receive storage materials.

5 The main object of this invention is to provide a casing of this type which is exceedingly strong and rugged, which is capable of bearing considerable loads on the exterior thereof, which is exceedingly true and square, and which is adapted 10 to relatively cheap and rapid manufacture and particularly adapted to rapid set up from machine made forms or blanks.

Another object of this invention is to provide 15 a casing construction which may be employed with thick corrugated cardboard, such as the double fluted corrugated type, which has a thickness of the order of one-half inch, with flap fastening means to aid in ease of erection and insure squareness and accuracy of set-up.

20 Another object of this invention is to provide a blank made of thick cardboard which when "set-up" will provide double side walls of the proper height so that all portions of the side walls will bear their share of the load.

25 These and many other objects, as will appear from the following disclosure, are secured by means of this invention.

This invention resides substantially in the combination, construction, arrangement, and relative location of parts as will be described in detail in the following specification and pointed out in the appended claims.

Referring to the drawing—

Figure 1 is a plan view of the blank of this invention;

35 Fig. 2 is a perspective view of the casing partly folded;

Fig. 3 is an end view of the completed casing; and

40 Fig. 4 is a side view of the completed casing.

Non-current records are generally stored in inexpensive solid or corrugated fibre storage files. The open ended file of the sliding drawer type, while encountering all the abuses of hard usage incident to the service, must also be very rigid and strong to permit of stacking in piles of considerable height.

45 Being incapable of front cross bracing, the back and sides particularly must be extremely rigid and stout. These strength requirements must be met, however, within low cost limitations, demanding a structure which incorporates all possible features tending toward rigidity and strength, and yet the blank of which may be 50 formed on standard machines with little waste.

These containers are shipped flat or "knocked down" as a thick strong blank of very sizable dimensions. Experience has shown these cases are often not set up square and correctly due to the tendency of the board to spring back to its 60 flat position. I have overcome this by incorporating locating means which aid in erection and are positioned to register the sides and back in square and insure true set up of maximum rigidity.

65 Referring to the drawing, the blank is shown comprising a single piece of thick cardboard having the portions 1, 2, 3, 4, 5, 6, 9, 10 and 14 all integrally united. The portions 2 and 3, when folded along the lines indicated at 11, form the 70 sides of the container; and the portion 1 forms the bottom. The portion 14 is folded along the line 17 to form the back of the container. The blank is so constructed that the back may be folded along the line 17 at a point to allow for 75 the thickness of the material. Thus the fold line 17 is offset from the adjacent edges of the sides 2 and 3 in an amount substantially equal to the thickness of the stock. This permits of the formation of a square container. Each of the 80 side portions 4 and 6 is of a width equal to the sides 2 and 3, plus an amount substantially equal to twice the thickness of the stock. The purpose of this will appear shortly. The flaps 9 and 10 are each equal to the width of the sides 85 2 and 3 plus an amount substantially equal to the thickness of the stock.

The side pieces 4 and 6 are folded at right angles to the top piece 5, as indicated in Fig. 2, along lines of fold 16 which are offset from the 90 lines of fold 11 by an amount substantially equal to the thickness of the stock. This again permits of a true, right angle corner with the side portions 4 and 6 in a position so that they will lie against and parallel to the side portions 2 95 and 3, as clearly indicated in Fig. 3.

The flaps 9 and 10 are folded along the lines 7 and 8 which are offset from the line of fold 15 a distance substantially equal to the thickness of the stock to again give square edges. 100 These flaps 9 and 10 are preferably of a sufficient length so as not to interfere with each other, as indicated in Fig. 2, when they lie parallel to the back portion 14. The back portion 14 is provided with locating means, as for example 105 such fasteners as indicated at 18, while their cooperating portions 19 are attached to flaps 9 and 10. These fasteners are positioned near the outer edges of portion 14 and adjacent to crease 17 (see Fig. 1) so that when the parts are folded 110

in position, as shown in Fig. 2, the engaged fasteners position the sides and flaps in true right angle relationship and confine the final hinging action along crease 17 insuring a correct square 5 set-up with maximum rigidity.

As is clear from Fig. 3, the extra width of the portions 4 and 6 insure that the edges of the outer sides 4 and 6, when the container is completely formed, will rest on the same plane 10 as the bottom 1, so that all of the side portions 2, 3, 4 and 6 will equally share any load placed on the container. It will be noted that the back of the container is also of double thickness and the height of the flaps 9 and 10 is such that 15 they will likewise bear their share of the load placed at the back of the container. These features of construction are particularly important in connection with thick board and when used in a container which is open at the front, as is 20 the container of this invention. Since the front of the container has no wall the construction disclosed is of particular importance because of the obvious advantage of properly bracing an open ended container.

When the parts are folded into the position shown in Fig. 3 they are secured in place by means of suitable fastening means, such as indicated at 25 and shown for purposes of illustration in the form of a gummed tape. If desired, the 30 raw edges of the stock which define the open end of the container may be finished off by securing pieces of tape 20 over them, as indicated in Fig. 1.

The container of this invention may be employed to directly receive materials for storage, 35 but is preferably used in connection with a suitable drawer which may likewise be made of cardboard, and which must freely slide thereon.

These features of construction are of particular importance when it is remembered that in 40 practice filing containers of this type are usually stacked one on the other and when they are all loaded the lower containers are subjected to sizeable compression loads.

Another important feature of the invention is 45 that the maximum of strength is secured from a single blank, which blank may at the same time be formed on standard machines, which is a matter of considerable economy. The lines of fold indicated by dotted lines in the drawing may be 50 provided on the blank either by creasing, by scoring, or slightly weakening the material along the proper line of fold, and the like.

From the above disclosure it will be apparent 55 that this invention resides in certain features

of construction which may be carried out in other ways and I do not, therefore, desire to be strictly limited to the disclosure as given for purposes of illustration but rather to the scope of the appended claims.

What I seek to secure by United States Letters Patent is:

1. A container blank as described comprising a single piece of foldable stock having a definite width at one end, an intermediate portion slotted to define folds, which portion has an overall width equal to the width of the first mentioned portion plus twice the thickness of the stock, and a third portion having a width equal to the width of said first portion plus four times the thickness of the stock, the blank when folded forming a container having double thickness side walls which evenly distribute vertical compression loads.

2. A blank of material foldable to form an open ended container of great strength and load bearing ability comprising a sheet of material of substantially rectangular proportions having successive sections of less width by twice the thickness of the material from one end to the other, each section being of uniform width throughout its length, the middle section being severed from the sheet at each side along a pair of perpendicular lines to form flaps.

3. A blank of material foldable to form an open ended container of great strength and load bearing ability comprising a sheet of material of substantially rectangular proportions having successive sections of less width from one end to the other, each section being of uniform width throughout its length, the middle section being severed from the sheet at each side along a pair of perpendicular lines to form flaps, and snap fasteners on said flaps and the middle section for securing the flaps in folded position.

4. A collapsible casing, open at one end, formed 115 from a single sheet of material of substantially rectangular shape by folding, the folding of the sheet defining three sections of uniform width, the middle section being narrower than the first section by twice the thickness of the sheet and the 120 third section being narrower than the first section by four times the thickness of the sheet, and L-shaped slots in the middle section forming back flaps, the sheet when folded forming a casing having sides of double thickness and vertical 125 height equal to that of the casing so that compression loads on the casing are carried uniformly by the sides.
